UNITED STATES PATENT OFFICE.

WILLIAM A. GIBSON AND CHARLES E. NEEDHAM, OF ALLENTOWN, PENNSYLVANIA,
ASSIGNORS TO BRADLEY PULVERIZER COMPANY, OF BOSTON, MASSACHUSETTS, A
CORPORATION OF MAINE.

AIR SEPARATOR.

Application filed November 18, 1921. Serial No. 518,511.

To all whom it may concern:

Be it known that we, WILLIAM A. GIBSON and CHARLES E. NEEDHAM, both citizens of the United States, residing at Allentown, ⁸ county of Lehigh, State of Pennsylvania, have invented an Improvement in Air Separators, of which the following description, in connection with the accompanying drawing, is a specification, like characters on the ¹⁰ drawing representing like parts.

This invention relates to improvements in air separators, in which the fine, finished material is separated from the coarser material by an ascending current of air, and ¹⁵ the principal object of the invention is to provide means for more effectively distributing the material to be separated, and subjecting the same to ascending and preferably radially projected currents of air which will ²⁰ carry only the fine, finished material upwardly and permit the tailings to drop into a suitable conveyer.

A further object of the invention is to provide means for regulating the ascending ²⁵ air currents.

A further object of the invention is to provide an improved means for supporting and actuating the fan which produces the air current and the mechanism which distributes ³⁰ the material to be treated.

These and other objects and features of the invention will more fully appear from the following description and the accompanying drawings, and will be particularly ³⁵ pointed out in the claims.

A preferred embodiment of the invention is illustrated in the accompanying drawings, in which—

Fig. 1 is a vertical sectional view through ⁴⁰ the casings of the air separator, showing the distributing mechanism and fan, and means for actuating the same, in elevation

Fig. 2 is a vertical longitudinal sectional view on an enlarged scale of the mechanism ⁴⁵ for supporting and rotating the fan and distributor.

Fig. 3 is a detailed view of a portion of the distributor plate and one of the distributing vanes secured thereto in angular ⁵⁰ relation to the horizontal plane of the distributor plate, and also angularly inclined backwardly from the radius of said plate.

The air separator illustrated in Fig. 1 of the accompanying drawing comprises a

preferably cylindrical casing 1, having a ⁶⁵ closed top 2 and a hopper-shaped bottom 3, provided with a conduit 4 through which the finished material may be discharged, and an inner, preferably cylindrical casing 5 ⁷⁰ concentric with the outer casing, having a top 6 provided with a central opening 7, the inner casing forming a separating chamber in which the material is distributed and separated.

A deflector 8, preferably of truncated conical form, is secured in the lower portion of the inner casing 5, and is provided at its lower end with brackets 9, which support a hollow, preferably conical member 10, provided with apertures desirably in the form of ⁷⁵ longitudinal slots 11. A cover 12, also of conical form, is fitted upon the conical member 10, and is pivotally mounted thereupon by a bolt 13 located in the axis of said conical member and cover. The conical cover member 12 is provided with a series of apertures ⁸⁰ preferably in the form of longitudinal slots 14, which correspond to the slots 11 in said conical member. Means are provided for rotarily adjusting the conical cover 12 in ⁸⁵ order that the width and area of the slots may be varied in accordance with the requirements of the separator. A convenient means for thus adjusting the conical cover 12, which is illustrated in Fig. 1, comprises a rod 15 ⁹⁰ preferably secured to the conical cover 12 by a ball and socket connection 16, said rod being provided with a screw-threaded end portion 17 which engages the complementary screw threads in a boss or ⁹⁵ bracket 18 secured to the outer side of the casing. A hand wheel 19 fixedly secured upon the outer end of the rod 15 provides means for rotating the same, so that the rod may be screwed inwardly or outwardly in ¹⁰⁰ the bracket 18 to adjust the position of the conical cover 12 relatively to the conical member 10, thereby varying the effective area of the openings through which air is projected into the separating chamber.

The lower end of the conical member 10 is located above the deflector 8 to provide an annular opening 20, through which the tailings may be discharged from the separating chamber. Any suitable means may be ¹⁰⁵ provided for carrying away the tailings. In the construction illustrated, a hopper 21 is provided for this purpose, which is sup-

ported upon brackets 22 depending from the deflector 8. The lower end of the hopper 21 communicates with a conduit 23, which extends through the wall of the hopper 3.

5 A continuously circulating current of air is produced by a fan 24 located in the space between the tops of the inner and outer casings, and provided with vanes 25 extending downwardly into the outer chamber 26 between the inner and outer casings.

10 Preferably vertically arranged baffle plates or partitions 27 are introduced in the chamber 26 between the inner and outer casings to direct the current of air produced by the 15 fan directly downwardly and to prevent a rotation of air in the chamber.

By reason of the construction aforesaid, the current of air produced by the fan is continuously circulated downwardly through 20 the chamber 26 between the inner and outer casings, and passes therefrom beneath the tapered lower end 28 of the inner casing upwardly through the space between the hopper 21 and the lower end of the truncated 25 deflector 8 into the hollow, preferably conical member 10 which extends upwardly into the separating chamber. The air is then projected through the apertures or slots 14 in the conical member 10 radially outwardly and 30 upwardly through the separating chamber, eventually passing through the central aperture 7 in the top of the casing which forms the separating chamber. The material is projected centrifugally into the path of the 35 radial and ascending currents of air which are produced by reason of the air passing through the apertures above described. By varying the area of these apertures, the character of the currents which act upon the material may be varied at will, so that the 40 separator may be adapted to operate efficiently upon materials of different quality. Such regulation also enables the separator to be set to deliver material of a predetermined fineness or quality.

45 A further object of the invention is to provide a more effective means for distributing the material to be separated in the upper portion of the separating chamber. In air separators heretofore constructed, the material has been usually distributed by being projected from the periphery of a horizontal circular plate, from which it is thrown off in substantially the plane of the upper surface 50 of the plate. The present improved distributor comprises a preferably horizontal rotating distributing plate 29 located in the upper portion of the separating chamber, and provided with a series of inclined vanes 55 30. The vanes are secured by suitable brackets 31 to the periphery of the plate 29, and desirably are inclined to the horizontal plane of the upper surface of the distributing plate 29 so that their rear edges are 60 higher than the plane of said plate. The

65 vanes also preferably are inclined backwardly from radii of said horizontal plate, as illustrated in Fig. 2. By reason of this construction, the material which is thrown off from the distributor plate 29 is projected vigorously upwardly and outwardly, thus causing a more complete separation of the particles of the material than has heretofore been obtained, and consequently enabling the ascending current of air more effectively 70 to engage and carry away the finer portions of the material.

75 Another feature of the invention comprises an improved means for supporting and rotating the distributor plate and the fan. In the construction illustrated, the distributor plate 29 is secured by a series of bolts 32 to a collar 33, which is secured upon a tubular supporting shaft 34, the separator plate 29 being spaced apart from the collar 80 33 by sleeves 35 surrounding the bolts 32. The tubular shaft 34 is secured to and supported by a gear 36, which is superimposed upon a gear 37, which is connected to a tubular shaft 38, which surrounds the tubular 85 shaft 34, and at its lower end is connected to and supports the spider 39 of the fan 24. The gear 37 is journaled in a bearing 40, which is carried by cross girders 41 secured to the top 2 of the outer casing. Suitable 90 bushings 42 are interposed between the inner tubular shaft 34 and the outer tubular shaft 38, and a suitable bushing 43 is also provided for the bearing 40.

95 The upper portion of the bearing 40 is provided with upwardly extending annular flanges 44, which form an oil chamber in which is situated the lower race 45 of a ball bearing. The upper race of said ball bearing is secured to the lower end of the gear 100 37. The gear 37 desirably is provided with a downwardly extending flange 48, which telescopes upon the outer flange 44 of the bearing 40. The anti-friction bearing, therefore, is so constructed that it may be 105 partially immersed in a lubricant, and the dust excluded from the lubricant by the telescoping flanges which surround the bearing. Suitable means may be provided for supplying the lubricant to the chamber in 110 which the bearing is situated. As illustrated, a conduit 49, which may be in the form of a grease cup, or may be connected to a forced feed oiling system, communicates through a duct 50 with one side of said bearing and an upwardly extending duct 51, the outlet of which is below the top of the flange 115 45, serves to discharge the excess of lubricant to a delivery pipe 52, which may conveniently be located upon the opposite 120 side of the bearing.

125 The gear 37 which drives the fan desirably is likewise provided with an upwardly extending annular flange 53, which forms a chamber to receive the lower race 54 of a 130

- ball bearing, the upper race 55 of which is secured to the lower end of the gear 36 which drives the distributor. A flange 56 telescoping upon the flange 53 of the lower gear 37, serves to exclude the dust from this upper bearing. Any suitable means may be provided for supplying oil or grease to the upper bearing.
- The material may be supplied to a hopper 57 carried upon the upper end of a pipe 58, which extends downwardly through the inner tubular shaft 34, and terminates a short distance above the centre of the distributing plate 29.
- Any suitable means may be provided for rotating the gears which drive the fan and the distributor respectively. As illustrated herein, the upper gear 36, which carries and rotates the distributor, is actuated through a pinion 59 upon a horizontal shaft 60, supported by suitable bearings upon the girders 41. The shaft 60 is provided with fast and loose driving pulleys 61 and 62.
- The gear 37 which actuates the fan is driven by a pinion 63 upon a shaft 64 mounted in suitable bearings, carried by the girders 41. Preferably means are provided for varying the speed of rotation of the fan. A convenient means comprises reversely disposed conical belt pulleys 65 and 66, carried respectively by the shaft 64, and a counter shaft having fast and loose driving pulleys 67 and 68. The belt, (not shown), passing over the conical pulleys 65 and 66, may be shifted in the direction of the axis of the conical pulleys to vary the speed of rotation of the shaft 64, and consequently the speed of rotation of the fan. Similar means may, if desired, also be provided for varying the speed of rotation of the distributor 29, but ordinarily it would be unnecessary to provide means for varying both the speed of rotation of the fan and the speed of rotation of the distributing plate.
- In the operation of the machine, the material to be separated is fed into the hopper 57, from which it passes downwardly through the pipe 58 upon the horizontal distributor plate 29, from which it is gradually projected centrifugally from the periphery of the plate. As the material passes from the periphery of the plate 29, it is caught by the angularly and rearwardly inclined faces of the vanes 30, and projected upwardly and outwardly in the upper portion of the separating chamber. By this construction, the material to be separated is distributed with substantial uniformity throughout the upper portion of the separating chamber.
- As the particles of the material are being projected in this manner, they are acted upon by the radially outward and upward currents of air which ascend through the apertures or slots in the conical member 10.
- The fine material which is carried by the ascending current of air passes upwardly through the opening 7 in the top of the inner casing, thence outwardly in the space between the tops of the inner and outer casing, and thence downwardly through the space between the inner and outer casing. The baffle plates 27 prevent a rotary motion of the air in this chamber, and also greatly facilitate the delivery of the fine finished material into the hopper 3, whence it is carried through the conduit 4 to a suitable bin or receptacle. The heavy material which is not carried away by the ascending air current from the separating chamber passes downwardly through the space 20, between the bottom of the conical member 10 and the deflector 8, and drops into the hopper 21, from which the rejected material, or tailings, is carried through the conduit 23 to a suitable receiver, or back to the grinding mill.
- It will be understood that the embodiment of the invention disclosed herein is of an illustrative character, and not restrictive, and that various changes in form, construction and arrangement of parts may be made within the spirit and scope of the following claims.
- Having thus described the invention, what we claim is new and desire to secure by Letters Patent is:
- An air separator comprising an outer closed casing and an inner casing spaced apart therefrom providing an inner and outer chamber, means for causing a current of air to pass continuously downwardly in one of said chambers, means for dividing said current of air into a plurality of currents and directing the same substantially radially and upwardly within and through the other chamber, means for projecting the material into the path of the ascending currents of air, means for delivering the finished material from the chamber having the descending current of air, and means for delivering the tailings from the chamber having the upwardly ascending currents of air.
  - An air separator comprising an outer closed casing and an inner casing spaced apart therefrom providing an inner and outer chamber, means for causing a current of air to pass continuously downwardly in one of said chambers, means for dividing said current of air into a plurality of currents and directing the same substantially radially outwardly and upwardly within and through the other chamber, means for projecting the material into the path of the ascending currents of air, means for delivering the finished material from the chamber having the descending current of air, means for delivering the tailings from the chamber having the upwardly ascending currents of air, and means for regulating the ascending currents of air.
  - An air separator comprising a closed

- outer casing having a delivery hopper for the finished material, an inner casing spaced apart therefrom providing an inner separating chamber, distributing means for projecting the material to be separated centrifugally in the upper portion of said separating chamber, means for delivering the tailings from said separating chamber, a hollow member centrally located within said separating chamber having apertured walls, and means for causing a current of air to pass continuously downwardly through the passage between said outer and inner casings and upwardly through said apertures in the wall of said hollow member into and through said separating chamber thereby producing a plurality of radially outward and upward currents in said separating chamber.
20. 4. An air separator comprising a closed outer casing having a delivery hopper for the finished material, an inner casing spaced apart therefrom providing an inner separating chamber, distributing means for projecting the material to be separated centrifugally in the upper portion of said separating chamber, means for delivering the tailings from said separating chamber, a hollow member within said separating chamber having apertured walls, means for causing a current of air to pass continuously downwardly through the passage between said outer and inner casings and upwardly through said apertures in the wall of said hollow member into and through said separating chamber thereby producing a plurality of radially outward and upward currents in said separating chamber, and means for regulating the size of the apertures in said hollow member.
5. An air separator comprising a closed outer casing having a delivery hopper for the finished material, an inner casing spaced apart therefrom dividing an inner separating chamber, distributing means for projecting centrifugally the material to be separated in the upper portion of said separating chamber, a hollow upwardly tapering apertured member located below and coaxially with said distributing means, means for causing a current of air to pass continuously downwardly through the passage between said outer and inner casings and upwardly through the apertures in said upwardly tapering member into and through said separating chamber thereby producing a plurality of radially outward and upward currents in said separating chamber, and means for delivering the tailings from said separating chamber.
6. An air separator comprising a closed outer casing having a delivery hopper for the finished material, an inner casing spaced apart therefrom dividing an inner separating chamber, distributing means for projecting centrifugally the material to be separated in the upper portion of said separating chamber, a hollow conical member located below and co-axial with said distributing means, having its wall provided with longitudinally extending apertures converging toward the apex of said hollow conical member, means for causing a current of air to pass continuously downwardly through the passage between said outer and inner casings and radially outwardly and upwardly through the apertures in said conical member, and means for delivering the tailings from said separating chamber.
7. An air separator comprising a closed outer casing having a delivery hopper for the finished material, an inner casing spaced apart therefrom dividing an inner separating chamber, distributing means for projecting centrifugally the material to be separated in the upper portion of said separating chamber, a hollow conical member located below and co-axial with said distributing means, having its wall provided with longitudinally extending apertures converging toward the apex of said hollow conical member, means for causing a current of air to pass continuously downwardly through the passage between said outer and inner casings and radially outwardly and upwardly through the apertures in said conical member, means for delivering the tailings from said separating chamber, a conical covering member superimposed upon said conical member, having apertures complementary to those in said conical member, and means for rotarily adjusting said conical covering member whereby the effective area of said apertures may be varied.
8. An air separator comprising a closed outer casing, having a delivery hopper for the finished material, an inner casing spaced apart therefrom providing a separating chamber, distributing means for projecting material to be supported centrifugally in the upper portion of said separating chamber, means including vertical baffle plates crossing the passage between the inner and outer casings for causing a current of air to pass continuously downwardly through the passage between the inner and outer casings and acting to prevent rotary movement of the air in said passage, means for dividing said current of air into a plurality of currents and directing the same radially and upwardly through said separating chamber.
9. An air separator comprising a closed outer casing having a delivery hopper for the finished material, an inner casing spaced apart therefrom providing an inner separating chamber, means for causing a continuous current of air to pass downwardly through the passage between said outer and inner casings and upwardly through said separating chamber.

- ing chamber, a rotatable horizontal centrifugal distributing plate located centrally in the upper portion of said separating chamber, provided with vanes having the planes 5 of the upper surfaces inclined to the horizontal and positioned to project the material fed upon said plate upwardly as it is discharged by the centrifugal action of said plate.
10. An air separator comprising a closed outer casing having a delivery hopper for the finished material, an inner casing spaced apart therefrom providing an inner separating chamber, means for causing a continuous 15 current of air to pass downwardly through the passage between said outer and inner casings and upwardly through said separating chamber, a rotatable horizontal centrifugal distributing plate located centrally in the upper portion of said separating chamber, provided with peripheral vanes having the planes of their upper surfaces inclined to the horizontal and also inclined rearwardly from radii of said plate and operable to project the material upwardly and outwardly as it is discharged by the centrifugal action of said plate.
11. A distributor for air separators comprising a rotatable circular plate provided 30 with peripheral vanes having the planes of their upper surfaces inclined to the plane of said plate and also inclined rearwardly from radii of said plate, and operable upon rotation of said plate to project the material deposited thereon upwardly and outwardly as it is discharged by the centrifugal action of said plate.
12. An air separator comprising a closed outer casing, having a delivery hopper for the finished material, an inner casing spaced apart therefrom, forming a separating chamber, means for delivering the tailings from said separating chamber, a rotatable fan located between the tops of said casings, 40 a distributor within said separating chamber, central, concentric, tubular shafts connected respectively to and supporting said fan and distributor, superimposed driving members connected to the respective tubular
- shafts and anti-friction bearings intermediate of the hubs of said driving members. 50
13. An air separator comprising a closed outer casing, having a delivery hopper for the finished material, an inner casing spaced apart therefrom, forming a separating chamber, means for delivering the tailings from said separating chamber, a rotatable fan located between the tops of said casings, a distributor within said separating chamber, central concentric tubular shafts connected respectively to and supporting said fan and distributor, a supporting bearing for the outer tubular shaft having an upwardly extending annular flange, a driving pinion connected to said outer tubular shaft, 60 provided with a flange telescoping the flange on said bearing, and an anti-friction bearing in the chamber formed by said telescoping flanges. 65
14. An air separator comprising a closed outer casing, having a delivery hopper for the finished material, an inner casing spaced apart therefrom, forming a separating chamber, means for delivering the tailings from said separating chamber, a rotatable fan located between the tops of said casings, a distributor within said separating chamber, central concentric tubular shafts connected respectively to and supporting said fan and distributor, a supporting bearing for the outer tubular shaft having an upwardly extending annular flange, a driving pinion connected to said outer tubular shaft, 70 provided with a flange telescoping the flange on said bearing, and also provided 75 with an upwardly extending annular flange, a pinion on the inner tubular shaft having a flange telescoping the upper flange on the driving pinion for the outer shaft, anti-friction bearings located respectively within 80 the chambers formed by said telescoping flanges, and means for supplying the oil to 85 said anti-friction bearings.

In testimony whereof, we have signed our names to this specification.

WILLIAM A. GIBSON.
CHARLES E. NEEDHAM.
